LOCKING SPIKE

Albert I. Israelson, Hartington, Nebr.

Application November 15, 1945, Serial No. 628,690

2 Claims. (Cl. 85—23)

1

This invention relates to spikes and securing means therefor wherein the spike when driven into wood or the like, will be effectively secured in place.

As used in railroad rail constructions, the spike is subjected to very severe strains. This is particularly true at the joints.

When the rails are laid, the spikes are driven in to the required depth, either with the common chair plate or some of the later improvements, or substitutes for the same. Each time the wheel of a car passes over a particular tie and its spikes, compression first takes place followed by a release of the pressure. This repeated action causes the ordinary spike to be lifted a small amount. After continued use, it is necessary to redrive the spikes to their former depth. After the second and successive times the spikes are driven in, they are more easily raised due to the fact that the holes are worn and are slightly larger.

In addition, when there is a space resulting from movement of the spike, in the wood, water is permitted to enter. This causes the hole to remain larger when and after it has been wet, swelled and dried out.

When water is so admitted, freezing takes place in winter, further disrupting the wood fibers and causing loose spikes after the freezing action is over.

In overcoming the difficulties of securing rails and ties together, various means have been used, some of which cut the fiber of the wood ties near or at the surface and open the spaces between the fibers to the admission of rain water. This rain water causes deterioration and rotting of the wood.

The primary object of this invention is the provision of an improved spike for the use on railroads or for securing metal to wood or wood to wood in general application.

Another object of the invention is the provision of a spike construction wherein a locking key secures the spike in place and leaves no open holes in the wood for the collection of rain water.

Another object of the invention is the provision of a suitable spike wherein a key is located in a slot or groove in the side of the spike, the main portion of the groove being located between the edges of one side.

A still further object of the invention is the provision of a spike which may be used with a plate through which it is driven and having a spring tending to draw upwardly on the spike

2

and a key to hold the spike in place, with means to positively hold the key in locking position.

Another and further object of the invention is the provision of a spike which may be used with a plate having an opening for the spike, a spring for normally tending to raise the spike and an edge to lock the key in place.

Another and still further object of the invention is the provision of a spike having a groove with a straight and curved section and a key in the groove, the key being so shaped as to always be pressed by the wood into the groove.

Another and still further object of the invention is the provision of a spike having a tapered body with a groove preferably parallel to the axis of the body of the spike.

Another and further object of the invention is the provision of a spike having a groove with straight and curved portions to guide a key into the wood and with provision for the extraction of the key when necessary—even though the spike and key are driven through an opening in a chair plate of only sufficient width to admit the spike and key when straight.

Another and still further object of the invention is the provision of a spike having a spring, the spike having a slightly downwardly extending lip from the spike head to hold the spring in place when the spike is in operative position.

Another and still further object of the invention is the provision of a spike assembly wherein when the spike and its spring hold a rail in place, the rail may be removed without withdrawal of the spike from the wood into which it has been driven.

Another and still further object of the invention is the provision of a spike assembly which will (1) be firmly held in the wood of the tie, (2) be provided with means for limiting the driving depth, (3) preventing effective bending of the spike shank away from the rail, (4) provide for limited movement of the rail without movement of the spike in the wood of the tie and (5) maintain a steady resilient pressure on the flange of the rail to hold the same in place.

Other and further objects will be apparent from a reading of the complete specification.

Referring to the drawing wherein are illustrated different embodiments and applications of the invention,

Fig. 1 is a side view of one embodiment of the invention, shown as applied to a railroad rail, the latter being in section.

Fig. 2 is a view taken at 90° from Fig. 1.

Fig. 3 is a top plan view of the structure shown on Figs. 1 and 2.

3

Fig. 4 is a view of the slot side of the spike. Fig. 5 is a side view of a key after it has been driven into its place.

Figs. 6 and 7 are side and edge views of the key respectively of Fig. 5.

Fig. 8 is a cross section on the line 8-8 of Fig. 4.

Fig. 9 is a side view of another adaptation of the invention.

Fig. 10 is a top plan view of the structure shown in Fig. 4.

Fig. 11 is a side view of another embodiment.

Fig. 12 is a view of the structure of Fig. 11 taken at 90°.

Fig. 13 is a top plan view of the structure illustrated in Figs. 11 and 12.

Fig. 14 is a side view of still another adaptation of the invention.

Fig. 15 is a view of the structure illustrated in Fig. 14 but from a point 90° from that of Fig. 14.

Fig. 16 is a top plan view of the structure illustrated in Figs. 14 and 15.

Fig. 17 is a side view of the spring illustrated in Figs. 14, 15, and 16.

Fig. 18 is a cross sectional view of an adaptation of my invention applied to a construction wherein two pieces of timber are secured together as in a bridge.

Fig. 19 is a top plan view of the structure shown in Fig. 18.

Fig. 20 is a side view of a spike having a body with sufficient taper to permit the spike and bent key to be withdrawn through a chair or other plate having an opening the width of which is substantially that of the larger part of the body of the spike.

Fig. 21 is a side view of a spike showing a cut away indentation to permit the locking end of the key to straighten out and enter the indentation to facilitate withdrawal.

Fig. 22 is a view of another form showing the cut away slot or indentation and showing the spike body of less taper than the taper of the body of the spike in Fig. 20.

Fig. 23 is a perspective view of three other adaptations of my invention—in the same installation.

Figs. 24 and 25 illustrate a still further adaptation of the invention showing a spike with a shoulder and a coil spring.

Figure 26 is a showing of a spike such as is illustrated in Fig. 22 in connection with a rail and a spring such as is shown in Fig. 14.

Figs. 27 and 28 are respectively cross sectional views on lines 27-27 and 28-28 of Fig. 26.

Referring particularly to Figs. 1 to 3, 10 designates the lower portion of a rail, 11 the chair or plate upon which the rail rests and which is provided with a hole 11a. My improved spike 12 is provided with a slot 12a which is located between the edges of the outer side and at its bottom has a curved portion 12b which extends across the face and to the edge of the spike.

A key 13 is provided and is originally straight. The thickness of this key 13 is slightly less than the width of the slot 12a and its width is more than equal to the depth of the slot 12a. This allows a portion of the key to extend outwardly beyond the face of the spike. The portion which extends beyond the face of the spike has an outer face, the upper or outer end of which is preferably outward of the lower or inner portion. This feature enables the upper portion to seal the opening in the wood against the entry of rain water. And by constructing the outer surface

4

of the key 13, straight, there is no pocket to collect water should it have a tendency to enter. Further, this construction causes the whole body of the spike and its key to be tightly bound in the wood into which it is driven.

As the key is driven into place, it follows the curved portion 12b of the groove and extends outwardly into the wood as illustrated in Fig. 2.

Surrounding the spike 12 and of resilient material, is a spring member 14 having an opening 14c. This spring member 14 has an extension 14a which rests upon the flange of the rail 10 and an oppositely extending extension 14b which may rest upon the chair or plate 11, or the tie.

The opening 14c in the spring member 14 is of a size to receive the shank of the spike 12 with sufficient space to drive the key 13 into its place but without much space to spare. This construction tends to make the chair or plate 11, the spike 12, the key 13 and the spring 14, a semi-rigid structure.

As the pressure of the trains cause compression and expansion of the wood in the tie 15, the extensions 14a and 14b will give and take—depending upon the movement of the rail 10. During this movement of the spring, the curved portion 13a of the key 13 being embedded in the wood of the tie 15, will prevent movement of the spike.

It is to be noted that the key-end is beveled in two directions as shown at 13b, 13c on Figs. 5 and 6. The bevel 13b assists the key to take its curving course in the wood, as shown in Fig. 2 and the bevel 13c tends to hold the key in the slot or groove 12a.

In driving the spike, when the track section 10 and chair 11 are in place, the spike is forced into the wood until the spring 14 is under tension tending to lift the spike out of the wood.

It is to be noted that the main portion of the groove 12a, above its curved portion, is intermediate the edges of the side face of the spike and is preferably parallel to the axis of the spike. This construction breaks a minimum number of fibers of the wood, permits the spike to be firmly held by its four edges and is given further stability by the key.

The shank of the spike, which is preferably slightly tapered, and the extension of the key beyond its slot, preferably fill the opening 14c in the spring member 14 when the spike is in place. This forms a semi-rigid connection preventing play between the members 12, 13 and 14. Since the main body of the key goes down straight with the wood, it cuts very few wood fibers, and the upper part of the key being at least as large as any other part of the key, the opening made by the lower part of the key is closed against the entrance of water by the part of the key at its upper end.

The spike 12 may be used with or without the chair or plate 11. When used with the plate 11, it may be necessary to withdraw the spike, as for example, when it is necessary to replace a rail. Since the opening in the chair or plate 11 is only of sufficient size to receive the shank or body of the spike and the protruding key, provision has been made to withdraw the spike through the opening 11a. The curved portion 12b of the groove is provided with a cut away portion 12c adjacent the outlet of the groove. This is illustrated in Fig. 22, the shape of the key being shown as it has been withdrawn from the wood. It is to be noted that when the key is so bent, the key and body of the spike occupy no more space than the upper portion of the spike body.

when passing through the opening 11^a of the chair or plate 11.

In the construction illustrated in Figs. 9 and 10, the spike 12 having a slot 12^a, 12^b and key 13, 13^a are similar to the corresponding parts illustrated in Figs. 1 to 8 already described. In this construction, the spring 94 has two extensions 94^a, 94^b which contact the flange of the rail 10. An opening 94^c permits the shank of the spike 12 to pass with preferably only sufficient room for the shank and the upper end of the key 13.

It is to be noted that the main body of the spring member is offset from a line through the centers of the extensions 94^a, 94^b. This is for the purpose of permitting the shank of the spike 12 to pass through the opening 11^a of the chair or plate 11, alongside the edge of the flange of the rail 10 and yet throw the extensions 94^a, 94^b to the side so that both of them will press downwardly on the flange of the rail section 10.

The operation of this construction is somewhat similar to the first described construction. The rail 10 and the chair or plate 11 being in place, the spike is passed through the opening 94^c and the opening 11^a in the chair or plate 11. While extensions 94^a, 94^b are held in contact with the flange of the rail 10, the spike is driven to the proper depth to place the spring 94 under sufficient tension to hold the rail flange in place.

After the spike has been driven to the proper depth, the key 13, as shown in Fig. 6, is inserted and driven in until it follows the curved portion 12^b of the groove and the end of the key 13^a has assumed the shape illustrated in Fig. 5. It will now be seen that with the upper end of the key held tightly with the spike in the opening 94^c, the rail will be resiliently held in place with no tendency for the rail flange to get a hold on the spike to lift it from its place. Moreover, the key holds the spike firmly in place in the wood.

Referring now to Figs. 11, 12 and 13, it is to be here noted that the spike 12 with its groove 12^a, 12^b, the key 13 with its curved portion 13^a all coact with the flange of the rail 10, the opening 11^a of the chair or plate 11 and the tie (not shown), as has been described for similar parts of Figs. 1 to 8.

The spring member 114 is provided with two extensions 114^a which are designed for contact with the chair or plate 11 as shown in Fig. 13. These extensions pass on either side of the shank of the spike 12. The extension 114^b extends toward and contacts the flange of the rail section 10. The opening 11^a in the chair or plate 11 is preferably so formed that it will maintain a tight contact with that part of the key 13 which extends beyond the groove 12^a of the spike and tends to hold the key in place.

When assembled, the spike is placed in the opening 11^a and driven into the tie. When nearly in place, the spring member 114 is slipped into place and the spike driven in until the spring is under the desired compression. The key is inserted and driven to its place as already described. To more securely hold the spring 114 in place, the spike head has a lip 12^d which extends over the top of the extension 114^b.

When used in this manner, the short lip 12^d will be between the extensions 114^a, which latter will be under the same tension.

Referring now to the form illustrated in Figs. 14, 15 and 16, the spike with its groove 12^a, 12^b, the key 13 with its curved portion 13^a, all coact with the rail 10, the opening 11^a of the chair

plate 11 and the tie, as has been heretofore described for similar parts of Figs. 1 to 8.

In this adaptation, the spring 144 has two extensions 144^a, 144^b, which, as in the case of the form shown in Figs. 9 and 10, both contact with the flange of the rail 10. In this form, the spring member 144 has a saddle 144^c in which the under side of the head rests, while the lip 12^d holds the spike head locked to the spring 144.

In use, the spike is placed in the opening 11^a of the chair or plate 11 and driven into the tie therebeneath until sufficiently low to engage the saddle 144^c of the spring member 144. The spring member 144 is then put in place with the lip 12^d over the edge of the saddle 144^c and the spike driven in until there is sufficient tension in the spring member. The opening of the chair plate is sufficiently small to engage the extending portion of the key when the latter is driven to its place as already described.

In Figs. 18 and 19, a form of the invention is illustrated wherein two timbers 15^a, 15^b are secured together. On the top of the timber 15^a is placed the plate 111 which has a center opening 111^a of a size and shape to permit passage of the body 12 of the spike. A spring member 214 is provided to perform a function similar to that of the spring member 14 illustrated in Fig. 1.

This spring member 214 may have as many as four arms 214^a and an opening 214^b to receive the body 12 of the spike. As in the previously described forms, the body 12 of the spike has a groove having a section 12^a which is substantially parallel with the axis of the spike and at its bottom a curved section 12^b to turn the key 13 into the wood of the timber 15^b, as at 13^a, Fig. 18.

In use, as on a wooden tread bridge, there is considerable up and down movement of the timbers. By this construction, the lower end of the spike is kept in place by the end 13^a of the key and when the pressure is released, the spring 214 restores the parts to their normal positions.

Figs. 20, 21 and 22 are to be understood as illustrating spikes having bodies which are tapered, less tapered and straight, respectively. Of the general shape of the heretofore described forms, is the shape shown in Fig. 21. However, it is to be understood that the forms illustrated in Figs. 20 and 22 may be substituted wherever a spike is shown assembled in the other views of the drawing.

In the forms of the spikes illustrated in Figs. 20, 21, 22, the bodies of the respective spikes are designated 12^x, 12^y and 12^z. It will be noted that in each of these forms, the key slot or groove is on a flat side, while in some of the previously described forms, the slot or groove is on a side having a chamfered end to form the point of the spike. This invention is adapted for use in either manner. The body of the spike may be tapered as to any two opposite sides or all four sides may be tapered.

In the case of sufficient taper to permit the end 65 of the key to be withdrawn without the necessity of a cut away place 12^c, the curved portion of the slot or groove is extended to the edge of the spike as illustrated in Fig. 20.

When the spikes are withdrawn from their operative positions, the keys assume positions illustrated in Figs. 20, 21 and 22.

In Fig. 23, the rail 10 is resting on a chair or plate 11 which is provided on each side of the rail with three openings 11^a through which the 75 spikes are driven into the tie. For the sake of

clearness, the showing of the tie and half of the plate 11, are omitted. The spike 12 is provided with a slot or groove 12^a, 12^b to receive the key 13 with its lower portion curved when put in place and having its tip beveled as at 13^b, 13^c as already described. The spike is provided with a lip 12^d which holds the pressure spring in place as will be described.

In the construction of the spike shown in Fig. 23, it is assumed that the size and strength of the keys make it impossible from a practical standpoint, to remove the spikes when, for example, it is desired to remove a rail section. The construction whereby the removal of the rail is made possible, will now be described.

The springs 314 have a saddle portion which engages the underside of the head of the spike and is held in place by the lip 12^d and the resiliency of the spring 314. The spring 314 is provided with an extension 314^a which engages the chair or plate 11 and with an extension 314^b which engages the rail to hold the latter in place.

The opening 11^a in the chair or plate 11 is placed with its inner edge adjacent the rail edge and is of sufficient size only to permit admission and driving of the spike 12. Since the spike is tapered, preferably on at least two sides, the opening 11^a will be of a size to permit the spike to fit snugly when it is driven to its operative position.

It will be obvious from the construction described that the spring may be forced out and the same or a new one replaced when, for example, it is desired to remove and replace a rail section. The removal and replacement of the 35 springs will be later described in detail.

Between the spikes 12 of Fig. 23, is shown a spike 112 which is illustrated with its head at 90° to the positions of the heads of the spike 12. A spring 514 has an extension 514^a for engagement 40 with the rail to assist in holding the rail in place. Two other extensions 514^b straddle the spike head of the spike 112 and engage the chair or plate 11.

The head of the spike 112 is so placed that its lip 112^d engages a saddle on the spring member 414 to press downwardly on the extension 414^a to hold the rail on the chair.

In the construction shown in Fig. 23, the two spaced spikes 12 hold the rail against lateral movement and exert some pressure on the rail flange. The intermediate spike 112 does not hold the rail against lateral movement but does exert a greater downward pressure on the rail flange than either of the spikes 12. This is due to the differences in the distances from the point of contact of the lip 112^d to the points of contact of the extensions 414^a and 414^b, the latter being longer than the former.

In assembling the structure illustrated in Fig. 23, the chairs or plates 11 being in place, the 60 rails are placed in position and the spikes driven in part way. The springs 314 are now placed under the lips 12^d and the spikes 12 driven home until the springs 314 are under the desired tension. With the spikes in this position, the keys are placed in their slots or grooves 13 and driven in. The ends following the curved portion 12^b of the grooves, will assume the positions illustrated at 13^a and will then emerge from the slot or groove and enter the wood, as already described.

The intermediate spike 112, is now driven in, the spring member 414 inserted and the spike 112 driven to its position. The key 13 is now driven in as already described and the construction is 75 complete.

In case it is desired, for any reason, to remove the springs 314, 414, it is only necessary to drive a small wedge under the overhanging end of the spike. This clears the spring from the lip 12^d. It is now possible to knock the spring to one side until it clears the spike. To replace the spring, a lever is placed under the lip 12^d with the spring below the lever. The spring 314 may, in this way, be compressed until it can clear the lip 12^d. A hammer may now be used to knock the spring to its place, after which the lever is released and removed.

To release the spring 514 from the spike head, a special two-pronged lever may be used, utilizing the short overhang 112^c of the spike head as a fulcrum, the two extensions 514^b being pressed down until the spring can be made to clear the lip 112^d. To replace, this spring may be driven or pried into place from its rail end, utilizing the special two-pronged lever to ease it into place.

In Figs. 24 and 25, are illustrated another form of spike for use with a coil spring. The spike 512 preferably has a tapered body, as illustrated. On one side of the spike body is a groove 512^a having a lower curved end 512^b. Unlike the spikes 12 and 112, the spike 512 has a shoulder 512^c, which shoulder 512^c is provided with a suitable lower surface to contact with the upper surface of the chair or plate 11.

The head 512^c is provided with a lip 512^d to hold the holding spring 514 in place. A tongue 512^e is provided on the lower side of the lip and extends into the coil of the spring 514 to act as a means for steadyng the spring 514 and for holding it in its place.

A locking key 513 having a curved end 513^a, when in place, is provided of a size to snugly fit in the groove 512^a and of a thickness to be, when in place, pressed firmly by the adjacent wood to minimize the wear due to movement when the parts are under pressure.

It is to be noted that the chair or plate 11 has openings which may be either adjacent the position of the edge of the flange of the rail or at a distance as illustrated in Fig. 25.

In utilizing this spike, the rail 10 and its chair or plate 11 are first placed in their relative proper positions. The spike 512 is now started to its seat through the opening 11^a of the plate 11. The spike is now driven in part way—until the spring 514 can be inserted over the tongue 512^e, under the lip 512^d. The spike is now driven to its place with the shoulder 512^c resting on the plate 11. In this position, there is a space below the bottom of the tongue 512^e. This space permits the slight changes in position in a vertical direction, of the rail flange of the rail 10.

The key 513 is now inserted in the groove 512^a and is driven in. As the point reaches the lower end of the groove, it follows the curved portion of the groove to the side of the spike where it enters the wood to lock the spike in its operative position. As the end of the groove is curved, the key enters the wood in the form of a hook, thus holding the key firmly in the tie and the spike is thus held firmly against the spring to press in turn, against the rail flange.

It will be thus clear that the parts will be held in proper relative positions with no bending of the spike outwardly from the rail and with no tendency for the rails to spread, yet permitting resilient slight movement in vertical direction.

As already noted for these spikes generally, the spike 512 may be provided with a cut away por-

tion 512^c similar in construction and function to the cut away portion 12^c of the spike 12. This cut away portion provides a space for the key to occupy if it should be necessary to draw the spike for any purpose.

While I have shown and described various adaptations of my invention, it is to be understood that the disclosure is merely illustrative and that modifications and changes may be made without departing from the spirit of the invention and within its scope as claimed.

Having described my invention what I claim is:

1. In combination, a spike comprising a shank of substantially rectangular cross section, a groove in a side of the shank and extending longitudinally thereof, a locking key for the groove, the groove being of substantially uniform cross section and extending from the spike head substantially parallel to one edge of the side and having a curved extension of similar cross section extending to one edge of the side, the shank being cut away at the end of the groove and toward its point to permit bending of the key end parallel to the spike axis and remain substantially in the cross section of the spike shank at its head end, the locking key being of a substantially uniform cross section and of a shape to substantially fill the groove and of a width greater than the depth of the groove to extend outwardly of the straight and curved sections of the groove and of a length to extend beyond the end of the groove when the key is in place.

2. In combination, a spike comprising a shank of substantially rectangular cross section, a groove of substantially rectangular cross section in a side of the shank and extending longitudinally thereof, a locking key for the groove, the

groove being of substantially uniform cross section and extending from the spike head substantially parallel to and adjacent one edge of the side and having a curved extension of similar cross section extending to the opposite edge of the side, the shank being cut away at the end of the groove and toward its point to permit bending of the key and parallel to the spike axis and remain substantially in the cross section of the spike shank at its head end, the locking key being of a substantially uniform cross section and of a shape to substantially fill the groove and of a width greater than the depth of the groove to extend outwardly of the straight and curved sections of the groove and of a length to extend beyond the end of the groove when the key is in place.

ALBERT I. ISRAELSON.
